UNITED STATES PATENT OFFICE.

THEODOR GIBON, OF CLARKSVILLE, TENNESSEE.

AEROPLANE.

SPECIFICATION forming part of Letters Patent No. 730,107, dated June 2, 1903.

Application filed November 19, 1902. Serial No. 132,033. (No model.)

To all whom it may concern:

Be it known that I, THEODOR GIBON, a subject of the Emperor of Germany, and a resident of Clarksville, in the county of Montgomery, State of Tennessee, have invented 5 certain new and useful Improvements in Aeroplanes, of which the following is a specification.

This invention relates to aeroplanes of the 10 construction described in my United States Letters Patent No. 710,266, dated September 30, 1902; and my improvements consist, mainly, in the provision of automatic means to normally tend to keep the aero-plane in 15 equilibrium and the combination therewith of means whereby the engineer or aeronaut may have the direction of flight under his perfect control.

In the accompanying drawings, Figure 1 is 20 an under side perspective view of my improved aeroplane in flight. Fig. 2 is a longitudinal section through the aeroplane. Fig. 3 is a plan view. Fig. 4 is an inverted plan. Fig. 5 is an enlarged perspective view 25 of the pendulum-valve. Fig. 6 is a diagram of the steering-valves and their connections, and Fig. 7 is a section of the valve V'.

The aeroplane is composed of a longitudinal hollow body C, with lateral wings W W', 30 preferably flat and hollow to contain the distributing-pipes. Within the body C are tanks T T' to provide a supply of suitable motive fluid. The upper and lower surfaces of the wings are provided with discharge-nozzle openings projecting aft in a slightly-inclined direction, as described in my patent and as indicated by the arrows, Fig. 2. The blasts of motive fluid emitted from these 35 openings propel the aeroplane by reaction.

A door D may be cut in the rear of the body, and discharge-nozzles n may be also located 40 at the rear of the body for propelling purposes. A pendulum-valve P is hung within the car, and the valve-casing is connected with the tank T by a supply-pipe t, Fig. 5. This valve has hollow casing or globe G to be secured to the body of the aeroplane, and it 45 has a central circular opening underneath. Around its horizontal equator are provided four openings 2, 3, 4, and 5, which are piped 50 to connect with certain discharge-nozzles in certain sections of the wings. These pipings

are indicated by dotted lines in Figs. 3 and 4. For example, pipe 2, Fig. 5, leads to discharge-nozzles 20 and 21 on the upper surface of the wings port and starboard forward, Fig. 3, and also with discharge-nozzles 22 23 port and starboard aft on the under or lower side of the wings, Fig. 4. Port piping 4 connects with nozzles 40 42 fore and aft on the upper port surface, Fig. 3, and with nozzles 41 43 fore and aft on the lower starboard surface, Fig. 4.

Rear pipe 3 connects with upper discharge-outlets 30 and 31 aft, Fig. 3, and also with 55 lower discharge-outlets 32 33 forward, Fig. 4. Starboard pipe 5 connects with upper discharge-outlets 51 and 53 on the starboard side, Fig. 3, and also with the lower discharge-outlets 50 and 52 on the port side, Fig. 4. 70

The valve proper is a hemispherical cup S, fitting the globe G and provided with a weighted pendulum p, acting on the tilting of the aeroplane to cut off connection between the interior of the globe and one or other of the 75 pipes 2, 3, 4, and 5 by moving the hemispherical valve-body S so as to overlap and close one of the said openings. As the aeroplane dips downward at its bow, for example, the upper margin of the valve S remaining 80 in a horizontal plane will cover the forward opening 2, and thus cut off the blast to the nozzles connected to it, as shown in Fig. 5. When the bow of the aeroplane rises, the cup-valve will cut off the opening 3. If the aero- 85 plane dips too far to port, the valve S will cut off the opening 4. If the aeroplane dips too far to starboard, the valve S will close the opening 5. This pendulum-valve thus 90 will tend automatically to maintain the aeroplane in equilibrium.

The aeronaut may have an inclosing shell s, overlooking the window w and in close proximity to valves V', V², and c, as described in my patent. These valves are hand-operated 95 and connect each one with four different discharge-nozzles in the wings. Thus valve V' connects with 1^a, 6^b, 7^a, and 2^a. Valve V² connects with 4^b, 5^b, 8^a, and 3^b, &c., as will be clearly seen on reference to the diagram, 100 Fig. 6.

The pipe t' leads from the tank T' and connects with the valves V⁵, V⁶, V⁷, and V⁸, each valve having four outlets to its casing (con-

nected as shown) V^5 , with branches 2^a and 1^a normally running free through valve V' , Fig. 7, while the branches 1^b 2^b normally run freely through valve V^3 . Valve V' besides the pipes

5 2^a and 1^a has pipes 7^a and 6^b , branched to valve V^6 . The shutting of valve V^5 closes the nozzles 2^a 1^a 1^b 2^b , thereby unbalancing the points at which reaction may take place on the surface of the aeroplane, while closing 10 valve V' shuts off 2^a , 6^b , 7^a , and 1^a . These valves are generally worked in pairs 1 and 2, 3 and 4, 5 and 6, 7 and 8 to provide different results, as hereinafter described.

In operation I prefer to start the aeroplane 15 in a closed-end upwardly-inclined tunnel fitting the rear cross-section of the device fairly accurately, then generating and admitting the driving-blast to all the nozzles, and thus cause the machine to soar upwardly into the 20 air and continue the trajectory of its flight until the pendulum-valve p accomplishes its purpose, to be now described more specifically. In this inclined position the opening 3 is closed by the cup S cutting off the upper 25 port and starboard aft discharge-nozzles 30 31 and the lower port and starboard forward nozzles 32 and 33, causing the blasts projected from the upper surface at the forward part and those projected from the lower surface 30 at the aft part to be in excess of the two upper aft sections and two lower forward sections, thereby causing the aeroplane to turn on its transverse axis 1 1 until a nearly horizontal position is reached, when the opening 35 3 will be uncovered and the pressure equalized on all sections of the wings.

Should the aeroplane in its flight take the position dipping its bow downwardly and to port openings 2 and 4 will be closed, Fig. 5, 40 stopping the reaction effect at nozzles 20 21, 22 and 23, 40 42, 41 43, and so bringing the aeroplane back to the desired nearly horizontal position. In like manner all sorts of combinations of dips will be automatically corrected by the pendulum-valve. On the other hand, by a suitable manipulation of the hand-controlled valves the aeronaut has it at all times within his control to direct the flight of the aeroplane. Thus should he desire to 45 steer to the right he will operate one or more of the valves to shut off the discharge at one or more points on the right side, preferably above and below equally. Again, if it be desired to descend the aeronaut will manipulate 50 one or more of the valves to shut off the discharges at 4^b 5^b , 4^a and 7^b , Fig. 3, on the upper side of both aft sections and also to shut off the discharges at 3^a 6^a , 3^b 8^a , Fig. 4, on

the lower side of both forward sections. Other directions of movement may be effected by 60 other manipulations of the hand-controlled valves, as will be readily understood.

I claim as my invention—

1. An aeroplane having reaction discharge-outlets in different sections of its wings with 65 a pendulum-valve having an inlet and a number of openings connected to said outlets, said valve being adapted to control the flow of motive fluid to outlets in the different sections to automatically keep the aeroplane in 70 equilibrium, substantially as described.

2. An aeroplane having reaction discharge-outlets in different sections of its wings, with a pendulum-valve, having an inlet and a number of openings connected to said outlets, and 75 adapted to automatically control the flow of motive fluid to said outlets in the different sections in combination with hand-operated valves adapted to control the flow to other outlets in the different sections to counteract 80 the automatic control when desired, substantially as described.

3. An aeroplane having wings, discharge-outlets in various sections of the wings, motive-fluid-supply piping to the wings, and 85 means inserted in the piping adapted to automatically shut off the supply from different sections of the wings as the aeroplane dips in various directions, substantially as described.

4. An aeroplane having a weighted pendulum-valve for controlling distribution of fluid-pressure to different discharge-outlets, a valve-casing comprising a hollow globe, an inlet-opening, and outlet-openings to the hollow 95 globe, said pendulum-valve being adapted to be swung by gravity so as to move the valve to cut off one or more of the said outlet-openings, substantially as described.

5. In combination with an aeroplane, a hollow globe, a pressure-inlet, fore, aft, port and starboard openings in the globe's surface connecting to various points of the aeroplane, a valve fitted within the globe, and having a pendulum depending from it, to move said 105 valve to automatically cut off certain required openings as the aeroplane dips, substantially as described.

In testimony whereof I have signed my name to this specification in the presence of 110 two subscribing witnesses.

THEODOR GIBON.
